UNITED STATES PATENT OFFICE.

LOUIS P. BAITINGER AND THOMAS H. BERKLEY, OF ST. LOUIS, MISSOURI;
SAID BERKLEY ASSIGNOR OF ONE-SIXTH TO SAID BAITINGER.

DESIGN FOR A HINGE MEMBER.

SPECIFICATION forming part of Design No. 31,084, dated June 27, 1899.

Application filed June 1, 1899. Serial No. 719,042. Term of patent 14 years.

To all whom it may concern:

Be it known that we, LOUIS P. BAITINGER and THOMAS H. BERKLEY, of the city of St. Louis, State of Missouri, have invented and 5 produced a new and original Design for a Hinge Member, of which the following is a full, clear, and exact description, reference being had to the accompanying drawings, forming a part hereof.

10 Figure 1 is a view in perspective of a hinge member embodying our new design. Fig. 2 is a plan view of the member seen in Fig. 1. Fig. 3 is a side elevation of the member.

As shown in the drawings, the leading or 15 material feature of our design consists of a rectangular plate 1, in which is formed a plurality of apertures 2, and integral with and extending laterally from the lower portion of one edge of the rectangular plate 1 is a gradually-tapered arm 3, integral with the top 20 edge of which is a rectangular body 4, and integral with the outer portion of said arm 3 and body 4 is the elongated rounded body 5,

the outer end 6 of which is extended upwardly and terminates in a semicircular lug 7. Passing vertically through the body 5 is a circular opening 8, and integral with the top of said body 5 and bounding said opening 8 is the vertically-extending semicircular flange 9. Integral with and projecting laterally from the center of the arm 3 is a plate 10, in which is formed a plurality of perforations 11, and at the point where this plate 10 joins with the plate 1 is a vertically-arranged rib 12, the same having a convex surface. 35

We claim—

The design for a hinge member, substantially as herein shown and described.

In testimony whereof we affix our signatures in presence of two witnesses.

LOUIS P. BAITINGER.
THOS. H. BERKLEY.

Witnesses:

ALBERT F. JACOBS,
J. R. F. MILES.
